UNITED STATES PATENT OFFICE

104,241

DESIGN FOR A CONSOLE EXTENSION TABLE

Carl H. Brandt, Hagerstown, Md., assignor to The Brandt Cabinet Works, Inc., Hagerstown, Md., a corporation of Maryland

Application March 22, 1937, Serial No. 68,344

Term of patent 7 years

• To all whom it may concern:

Be it known that I, Carl H. Brandt, a citizen of the United States, residing at Hagerstown, in the county of Washington and State of Maryland, have invented a new, original, and ornamental Design for Console Extension Tables, of which the following is a specification, reference being had to the accompanying drawings, forming part thereof, in which:—

Fig. 1 is a perspective view of a console extension table, showing my new design, with the hinged top portion elevated to a vertical position;

Fig. 2 is a side elevation thereof, with the extension leg pulled out and the hinged top portion lowered thereon;

Fig. 3 is a side elevation thereof, with the extension leg pushed in and the hinged top portion swung over to closed position;

Fig. 4 is a similar view to Fig. 3, but with the hinged top portion raised to a vertical position; and

Fig. 5 is a front elevation thereof, showing the top closed.

I claim:—

The ornamental design for a console extension table, as shown.

CARL H. BRANDT.
